UNITED STATES PATENT OFFICE

2,007,466

HIGHWAY GUARD FENCE

Calvin Campbell, Denver, Colo., assignor to The Colorado Fuel and Iron Company, Denver, Colo.

Application August 30, 1932, Serial No. 631,047

17 Claims. (Cl. 256—13.1)

This invention relates to highway guard fences of the type in which a resilient barrier is suspended forwardly of a series of posts set at an edge of a highway. A fence of this type is disclosed in United States Patent No. 1,776,517, of Charles H. Macdonald, granted September 23, 1930, and also in an application for patent of the same inventor, Serial No. 284,442, filed June 11, 1928, and allowed June 10, 1932.

The fence, as disclosed in the patent and application for patent, comprises cables or other laterally movable elements for the suspension of a barrier forwardly of the posts. The barrier has been shown as composed of cables either with or without a wire netting, and it is an object of the present invention to provide in connection with the suspension elements above referred to, a barrier composed of one or more "flats" of inherently resilient metal.

Another object resides in a novel method of securing the barrier to the supports projecting forwardly from the posts, and a further object is to provide certain improvements in the construction of the supports or suspension-elements themselves.

In the accompanying drawings in the several views of which like parts are similarly designated,

Figure 1 is a diagrammatic plan view of a guard-fence at the side of a highway.

Figure 2 is a vertical cross section of a highway guard fence of the improved construction, taken on the line 2—2 of Figure 1.

Figure 3 is a fragmentary face-view of the fence, looking in the direction of the arrow 3 in Figure 2.

Figure 4 is a cross-section similar to that of Figure 2, showing a different construction of the barrier.

Figure 5 is a face-view of the barrier shown in Figure 4, looking in the direction of the arrow 5.

Figure 6 is a section on the line 6—6 of Figure 4.

Figures 7 and 8 are vertical cross-sections of the fence, showing modifications in the form and construction of the means for suspending the barrier forwardly of the posts.

Figure 9 is a fragmentary face-view of one of the cables of the barrier shown in Figures 7 and 8, looking in the direction of the arrows 9.

Figure 10 is an enlarged view of the connection between the barrier and the suspension means of a fence of the construction shown in Figures 2 and 3.

Figure 11 is a top view of the parts shown in Figure 10.

Figure 12 is an enlarged view of the connections between the barrier and the suspension means of a fence of the type shown in Figures 4 and 5.

Figure 13 is a top view of the parts shown in Figure 12.

Figure 14 is an enlarged view of one of the connections between the barrier and the suspension means of a fence of the forms shown in Figures 7 and 8.

Figure 15 is a top view of the parts shown in Figure 14.

Figure 16 is an enlarged side view of a connection between the barrier and the suspension means of a fence of the constructions shown in Figure 8.

Figure 17 is a sectional plan view of the parts shown in Figure 16, and

Figure 18 is a section taken on the line 18—18 of Figure 14.

Referring further to the drawings, the posts 5 from which the barrier is suspended, are preferably made of two angle bars 6 set in a block 25 of concrete 7 in parallel and spaced relation to each other. It is to be understood, however, that posts otherwise constructed, may be used within the scope of the invention.

In the construction shown in Figures 2, 3, 10 30 and 11, the elements by which the barrier is suspended from the posts, each comprise an endless cable 8 turned around three bolts 9 in the space between the members 6 of which the post is composed, and tensioned by a fourth bolt 10 35 similarly mounted on the post, between the others. The cable is projected forwardly of the post in two substantially parallel sections 8a at the apexes of which the barrier is fastened.

The barrier consists of two metal ribbons or 40 flats 12 fastened at the apexes of the suspension element by means of clamps 13. The clamps, as best shown in Figures 10 and 11, each comprise two lapping members 13a and 13c of U-shaped form, pivotally connected by headed pins 14. 45 The pins are held against vertical displacement by cotters 15 in apertures at their projecting ends.

The flat 12 of the barrier is disposed between the two members, free for longitudinal movement and the clamp is secured at the respective apex 50 of the cable by drawing the latter through openings in the member 13a and securing the latter in place by means of U-bolts 16 and nuts 17.

The cables 8 are made into endless form by splicing their lapping ends by means of U-bolts 55

18 and nuts 19, as shown in Figure 2. Distinctive features of the fence are that the barrier-members 12 are free for longitudinal movement, that they are pivoted for lateral movement relative 5 to the suspension-elements, and that they are vertically adjustable for alinement with reference to the road-surface by loosening the U-bolts 16 and lengthening or shortening one stretch of the cable section relative to the other. Further 10 adjustments may be made by shortening or lengthening the cable by relative adjustment of the spliced ends thereof, and/or by moving the cable relative to the post, it being apparent that the several bolts around which the cable is stretched 15 cooperate to frictionally hold the cable in adjusted positions.

In a fence of the above-described construction, the barrier is free to give under impact by the inherent resilience of its two flats, by the 20 movable connection of the latter with the suspension cables, and by lateral movement of the latter with reference to the respective posts.

The form of the invention illustrated in Figures 4, 5, 12 and 13 differs from that hereinabove 25 described, mainly in that the barrier is composed of a single plate or "flat" 20 of greater width than either of the two ribbonlike flats 12. The suspension-element consists of a cable 21 connected with the post as before, but having a single forwardly 30 projecting portion of substantially trapezium form.

The forward side of the cable lies flat against the rear side of the plate 20, and the latter is secured to the cable by a clamp 22 which embraces the plate and which in divergently extending ends 22a, has openings through which 35 the cable is passed. The clamp is secured at its ends to the cable by U-bolts 23, and, as before, the cable and the barrier are adjustable to aline 40 the barrier with the surface of the road. The barrier is lengthwise movable relative to the suspension-elements and the latter are spliced at the ends of their cables, as in the first described form.

45. In the construction illustrated in Figures 7 and 8, the barrier consists of two or more cables 24 which are connected at the forward ends of suspension cables 25, by means of clevises 26. The suspension cables are supported and tensioned on the posts by the bolts 9 and 10 as in the before described construction.

In Figure 7, the forwardly projecting suspension cable is of trapezium form, as in the construction shown in Figure 4, and the two cables 50 of the barrier are supported at the forward corners of the suspension cables by the clevises above referred to.

Each clevis has a U-shaped loop embracing the cable, and apertures at the ends of the loop through which the suspension-cable passes. The clevises are secured to the suspension cable by U-bolts 27 applied to extensions at an end of their loops, and tightened by nuts 28.

60. It will be understood without further illustration that all of the above described adjustments and resilient movements of the barriers of the constructions shown in Figures 2 and 4, are present in those illustrated in Figures 7 and 8.

70. The construction of Figure 8 differs from that of Figure 7 in that the barrier is composed of three parallel cables instead of two, the third or intermediate cable 31 being suspended by means of cables 29 looped around bolts 30 on the posts, and connected with the cable 31 by clevises 32 of

the same construction as those hereinbefore described.

The cables of the barriers of Figures 7 and 8 may constitute a barrier per se, or they may form a support for a netting of the character shown in the patent and application for patent hereinbefore referred to. The barrier is anchored at its extremities to end posts of the series, as shown at 33 in Figure 1, preferably in a manner disclosed in a separate application, Serial No. 631,048, for patent filed simultaneously with the present application. 10

What I claim and desire to secure by Letters Patent is:

1. In a highway guard fence, a series of posts, 15 suspension means projecting forwardly thereof in trapezium form, a barrier, and a barrier-embracing connection fastened at the forward part of the suspension means, the barrier being free for lengthwise movement in said connection. 20

2. In a highway guard fence, a series of posts, a suspension-cable projecting forwardly thereof in trapezium form, a barrier, and a barrier-embracing connection fastened at the forward part 25 of the suspension-cable, the barrier being free for lengthwise movement in said connection.

3. In a highway guard fence, a series of posts, a suspension-cable projecting forwardly thereof in trapezium form, a barrier, and a barrier-embracing connection fastened adjacent an end of 30 the forward part of the suspension-cable.

4. In a highway guard fence, a series of posts, a suspension-cable projecting forwardly thereof in trapezium form, a barrier, and a barrier-embracing connection fastened adjacent the ends of 35 the forward part of the suspension-cable.

5. In a highway guard fence, a series of posts, 40 suspension means of substantially trapezium form projecting forwardly thereof, barrier-members at opposite ends of the forward part of the suspension means, another barrier-member between the first-mentioned members, and a barrier-embracing connection on the suspension-means, the barrier being free for lengthwise movement in said connection. 45

6. In a highway guard fence, a series of posts, a suspension-cable projecting forwardly thereof, 50 a barrier, and a barrier-supporting connection including a member having an opening through which the cable is passed, and a member clamp-ing the first member to the cable.

7. In a highway guard fence, a series of posts, a suspension-cable projecting forwardly thereof, a barrier, and a barrier-supporting connection including 55 a member having an opening through which the cable is passed, and a U-bolt securing said member to the cable.

8. In a highway guard fence, a series of posts, a suspension cable projecting forwardly thereof, a barrier, and a barrier-supporting connection 60 including a barrier-embracing member, and means to adjustably clamp said member to the cable.

9. In a highway guard fence, a series of posts, a suspension cable projecting forwardly thereof, 65 a barrier and a barrier-supporting connection including a barrier-embracing member, and a U-bolt fastening said member to the cable.

10. In a highway guard fence, a series of posts, a suspension cable projecting forwardly thereof, 70 a barrier, and a barrier-supporting connection including a U-shaped barrier-embracing member, a U-shaped member fastened to the cable, and means for the connection of said members.

11. In a highway guard fence, a series of posts, 75

5 a suspension cable projecting forwardly thereof, a barrier, and a barrier-supporting connection including a U-shaped barrier-embracing member, a U-shaped member fastened to the cable, and means for the pivotal connection of said members.

10 12. In a highway guard fence, a series of posts, a flexible suspension-member projecting forwardly thereof and adapted for movement longitudinally of the barrier, and a barrier slidably secured at the forward end of said suspension-member.

15 13. In a highway guard fence, a series of posts, a movable suspension-member projecting forwardly thereof, and a barrier slidably secured at the forward end of said suspension-member, the barrier and the suspension-member each being adapted for separate movement relative to the other, longitudinally of the barrier.

20 14. In a highway guard fence, a slotted post, a barrier-suspending member on the post, and a plurality of guides in the slot in substantial vertical alinement, two of said guides being relatively close together and the member being supported by the guides and engaging the close-together guides on opposite sides thereof, whereby to tension the member within the slot.

25 15. In a highway guard fence, a post, a cable projecting forwardly therefrom in endless form, a barrier-suspended at the forward part of the cable, the ends of the cable lying together in overlapping relationship, and a plurality of clamping means binding the ends and capable of being loosened separately, whereby to permit adjustment of the length of the cable, free from stress.

10 16. In a highway guard fence, a series of posts, a suspension-cable projecting forwardly thereof, a barrier-supporting connection, including a U-shaped barrier-embracing member and means to secure the ends of said member to the cable, and a barrier loosely supported in the U-shaped member for sliding movement lengthwise of the series of posts.

15 17. In a highway guard fence, a series of posts, a suspension-cable projecting forwardly thereof, a barrier-supporting connection, including a barrier-embracing member and a member fastened to the cable and in pivotal connection with the first member, and a barrier loosely supported in the barrier-embracing member for sliding movement lengthwise of the series of posts.

25

CALVIN CAMPBELL.
